UNITED STATES PATENT OFFICE

2,678,490

SAFETY RAZOR ADAPTER

William D. Winslow, Vineland, N. J.

Application February 10, 1949, Serial No. 75,689

2 Claims. (Cl. 30—89)

1

This invention relates generally to safety razors of the type which employ double-edged blades, it being among the principal objects of the present invention to provide means which adapt the razor head to be angularly adjusted in either one of two positions so that it may be operated upon either a pull or push stroke as may be most convenient to the person using the razor.

More particularly, it is an object of the present invention to provide an exceedingly simple and inexpensive adapter for a conventional double-edged blade type of safety razor which is designed to pivotally support the razor head in either one of two adjusted positions, the head being held in either adjusted position by the hand of the person using the razor and being instantly convertible from one to the other of its adjusted positions without necessitating the use of any special resetting devices or tools.

Other objects and advantages of the present invention will appear more fully hereinafter, it being understood that the present invention consists substantially in the combination, construction, location and relative arrangement of parts, all as described in detail hereinafter, as shown in the accompanying drawings and as finally pointed out in the appended claims.

In the accompanying drawings—

Figure 1 is a perspective view showing the razor with its head held in adjusted position for a push stroke of the shaving blade;

Figure 2 is a perspective view showing the razor with its head held in adjusted position for a pull stroke;

Figure 3 is an end elevational view of the razor with parts thereof shown in section;

Figure 4 is a side elevational view of the razor head and the adapter of the present invention associated therewith;

Figure 5 is a perspective view of the adapter per se; and

Figure 6 is a vertical sectional view of the adapter as taken on the line 6—6 of Figure 5.

Referring now more particularly to the drawings, it will be observed that the present invention is embodied in a safety razor of conventional type having a blade supporting head 10 and a handle 11, the head including a pair of cooperating clamp members 12 and 13 which are adapted to clampingly secure therebetween a double edged wafer type of blade of conventional construction. In this conventional type of razor the blade clamping member 12 is provided with an externally threaded stud 14 adapted to be re-

2

ceived in an internally threaded recess 15 suitably provided in the upper end of the handle 11, it being apparent that when the stud is securely threaded into the handle the clamping members 12 and 13 are drawn tightly together to securely clamp the shaving blade therebetween with the shaving head rigidly fixed with respect to the handle.

In accordance with the present invention, an adapter unit, designated generally by the reference numeral 16, is so disposed operatively between the shaving head 12 and its handle 11 as to permit the head to be swung into either one of the two operative positions respectively shown in Figures 1 and 2. With the shaving head swung into its position as shown in Figure 1 the razor is adapted to be operated on a push stroke, as by pushing it upward on the side of the face, while when the razor head is swung into its position as shown in Figure 2 it may be operated on a pull stroke, as by pulling it downwardly on the side of the face, in which latter case either edge of the blade may be employed.

As appears most clearly in Figures 3 to 6, inclusive, the adapter 16 of the present invention comprises a yoke member 17 having a U-shaped body portion 18 terminating in a depending externally threaded stud 19, in association with an upper member 20 which is pivotally mounted between the laterally spaced parallel side arms of the yoke member by a transversely extending pivot pin or bolt 21. The pivoted upper member 20 of the adapter is provided with an internally threaded socket 22 into which is adapted to be threaded the stud 14 of the shaving head, the depending threaded stud 19 of the adapter being in turn adapted to be threaded into the threaded recess 15 in the upper end of the razor handle 11.

It will be apparent that when the razor head and handle are respectively threaded on to opposite ends of the adapter 17 the razor head is capable of being swung relatively to the handle 19 about the axis of the pivot pin 21, the threaded connections between the razor head and the adapter being such that when the head with the shaving blade mounted therein is securely threaded on to the pivoted supporting member 20, the opposite shaving edges of the blade both extending parallel to the axis of the pivot pin 21.

In order to instantly swing the head into one or the other of its two operative positions respectively shown in Figures 1 and 2, the pivoted member 20 of the adapter is provided at one side thereof with a depending extension 23 of a length

sufficient to project below the base of the U-shaped member 18 and overlie the upper end of the razor handle 11, the extension being adapted for ready engagement by the thumb or forefinger of the hand of the person holding the razor during the shaving operation. It will be apparent that the extension 23, when in engagement with the base of the yoke member 17, as shown in Figures 2 and 3, serves to limit the permissible swing of the razor head about the pivot pin 21 in one direction, while engagement of the upper member 20 with the opposite edge of the yoke 17 as shown in Figure 1 limits permissible swing of the razor in the opposite direction.

When it is desired during use of the razor to operate it on a push stroke, it is merely necessary to press the thumb or forefinger of the hand upwardly against the extension 23, as shown in Figure 1, whereupon the razor head is securely held in position with its shaving edge adapted to be pushed upwardly against the side of the face. On the other hand, when it is desired to operate the razor on a pull stroke, the extension 23 is pressed by the thumb or forefinger of the hand holding the razor flatwise against the upper end of the handle 11 so as to securely maintain the razor head in position to permit either of the shaving edges of the blade to be pulled downwardly along the side of the face or other surface of the body to be shaved.

It will be understood that the adapter 17 of the present invention may be manufactured and sold as an accessory adapted to be employed in connection with conventional safety razors having a head which is threadedly secured to a handle 11 in accordance with conventional principles to thereby modify such conventional razor and permit it to be operated for either push or pull stroke as hereinbefore described, or the adapter may be incorporated in the upper end of the handle 11 as a built-in component part thereof. It will be understood also that the present invention is susceptible to various changes and modifications which may be made from time to time without departing from the general principles or real spirit thereof and it is accordingly intended to claim the same broadly, as well as specifically, as indicated in the appended claims.

What is claimed as new and useful is:

1. An adapter for insertion between the head assembly and handle of a safety razor, said adapter comprising a pair of members adapted to be fixedly secured, respectively, to said head

assembly and handle, one of said members being provided with a bifurcated end portion and the other of said members being provided with an end portion engaging between said furcation, means for pivotally connecting said end portions for bodily swinging movement of said head assembly from a position wherein it is disposed in conventional relation to said handle for pull-stroke shaving to a position wherein it is disposed to one side of said handle for push-stroke shaving, and a rigid element integral with the one of said members proximate said head assembly, said element being disposed in longitudinal continuation of said one member on the side of said pivot remote from said head assembly for securing of the latter in either of the aforesaid positions by the application of finger pressure on said element.

2. An adapter for insertion between the head assembly and handle of a safety razor, said adapter comprising a yoke member threadedly engageable in the end of said handle, a supporting member threadedly engageable with said head assembly, means for pivotally mounting said supporting member in said yoke member for bodily swinging movement of said head assembly from a position wherein it is disposed in conventional relation to said handle for pull-stroke shaving to a position wherein it is disposed to one side of said handle for push-stroke shaving, and a rigid element integral with said supporting member, said element being disposed in longitudinal continuation of said supporting member on the side of said pivot remote from said head assembly for securing of the latter in either of the aforesaid positions by the application of finger pressure on said element.
